(57) **CLAIM**

The ornamental design for a rotary union, as shown and described.

DESCRIPTION

FIG. 1 is a perspective view taken from the front, top, and left side of a rotary union in accordance with my new design. FIG. 2 is a left side elevational view of the rotary union of FIG. 1.

FIG. 3 is a right side elevational view of the rotary union of FIG. 1.

FIG. 4 is a front elevational view of the rotary union of FIG. 1.

FIG. 5 is a rear elevational view of the rotary union of FIG. 1.

FIG. 6 is a top elevational view of the rotary union of FIG. 1; and,

FIG. 7 is a bottom elevational view of the rotary union of FIG. 1.

The broken lines shown depict portions of the rotary union that form no part of the claimed design.
